[57] CLAIM

The ornamental design for support trim rail assembly for panel wall system, as shown and described.

DESCRIPTION

FIG. 1 is a fragmentary perspective view of an assembled support of trim rails for a panel wall system, the broken line depiction of the flange being for illustrative purposes only and forming no part of the claimed design;

FIG. 2 is a fragmentary front elevational view thereof;
FIG. 3 is an enlarged fragmentary bottom plan view taken along line 3—3 of FIG. 2, and is broken in the center for ease of illustration; and,

FIG. 4 is an enlarged fragmentary side elevational view taken along line 4—4 of FIG. 2, and is broken in the center for ease of illustration.

The pattern of the support trim rail assembly for panel wall system shown in FIGS. 1 and 2, is repetitive throughout the length and width of the design.
